OIL BURNER

Floyd W. Bentley, Brooklyn, N. Y.

Application December 6, 1941, Serial No. 421,896

6 Claims. (Cl. 158—77)

This invention relates to oil burners and has for an object the provision of improvements in this art.

As greater efficiency is demanded in oil-burner installations, the demand being most insistent in the industrial field, it becomes increasingly desirable to use highly superheated air for atomizing and burning the fuel. If air temperatures up to 650° F. could be used, the combustion efficiency would be greatly improved over present practices. It is, indeed, possible to employ such highly heated air in burners of the gun type, but it is desired to use it in the much more efficient rotary type burner; and here the necessary proximity of the rotor drive motor to the burner and hot air manifold has caused such overheating of the motor and its bearings as to make its use impractical. It has been proposed that liquid cooled bearings be used, but this has proved equally unsatisfactory.

According to the present invention, the use of a motor close to the hot air manifold is made feasible by improved assembly and cooling means which provide for the maintenance of a low operating temperature for the motor and the rotor shaft bearings.

The objects, advantages and novel features of the invention will be made manifest by the following description of an illustrative embodiment of the invention, reference being made to the accompanying drawings wherein:

Fig. 1 is a front elevation of an oil burner installation embodying the present invention;

Fig. 2 is a corresponding plan view; and

Fig. 3 is a vertical section taken on the line 3—3 of Figs. 1 and 2.

Referring to the drawings, the numeral 10 denotes a refractory lined combustion chamber or firebox of a furnace. A burner 11 and a plurality of ducts 12 for a supply of secondary air provide the source of heat for the firebox. The manifold 13 for the secondary air around the firebox is not completely shown but this is a common arrangement and concerns the present invention only as a region of high temperature adjacent the oil burner motor 14 and the bearings 15 of the tubular shaft 16 of the burner spinner cup 17. A manifold 18 for primary combustion air at high temperature (say up to 650° F. or above) constitutes an even closer region of heat which is normally injurious to the motor and its bearings. A temperature above 300° F. at the motor or spinner shaft bearings is not permissible. Preferably a much lower temperature is maintained.

Oil is injected into the spinner cup 17 through

5 a nozzle 20 on the end of a fixed oil supply tube 21 mounted coaxially within the spinner shaft 16. The tube 21 is mounted on a support 22 secured to the motor casing.

10 The air from the primary air manifold 18 enters the firebox around the spinner cup 17 by way of a coaxial duct 25 and serves to break up the oil which is thrown off as a cone-shaped sheet from the end edge of the spinner. The circumferential inclination of vanes 26 within the tapered end of the air duct 25 has an effect upon the spread or conical pitch of the resulting flame from the burner.

15 Heated air for the primary air manifold may be derived from a blower 27, and if desired this same blower may supply air to the ducts 12 of the secondary air manifold 13.

20 The burner 11, motor 14, manifold 18 and closely related parts are mounted on a closure plate 30 carried on a hinge 31. The oil line 32 to oil tube 21 is jointed on the hinge line, and the manifold 13 is connected to a fixed air conduit 33 when the plate 30 is in closed or operative position. The plate 30 may be retained in closed position by securing devices 34. The conduit 33 may be provided with a flow controlling damper 35.

25 The novel means which make practical the use of a spinner motor and bearings so close to the region of high temperatures in the preheated air manifolds comprise devices for creating a separating wall of cool air between the motor and bearings and the hot zone. It is to be noted that there are no bearings for the spinner shaft 16 within the hot zone of the manifold 18, hence the bearings 15 which support the shaft must be located as near as possible to the manifold.

30 The means herein illustrated for maintaining this separating wall of cool air comprise a conical shield 40 of such size as to completely screen the motor from the proximate hot zones. The shield is shown to be secured to the manifold 18, as by bolts 41, heat insulation 42 being provided, if desired, to minimize heat conduction between the connected parts. Spatial separation instead of, or in addition to, the heat insulation may be employed and heat conduction may be further minimized by securing the shield to the motor casing or to the motor support 43 instead of to the manifold 18.

35 The shield 40 may be of good heat conducting material, such as metal, and is provided with generally radial cooling vanes 44 on one or both sides, here shown on the inner side.

40 A secondary shield is provided by a plate 45 which is secured within the conical shield, as

by bolts 46. At its inner edge the flat plate 45 is spaced from the shaft 16 to provide intake air passages 47 by which cool air is drawn in, against the shield 40 in a manner to be hereinafter described, passing en route over that part of the motor and the bearings 15 which are nearest said intake passages. At its outer edge the plate 45 is spaced from the conical shield 40 to provide ample outflow air passages 48. Inturned or welded fingers 49 at circumferentially spaced points around the conical shield provide convenient means of attachment of the parts by the bolts 46.

A forced circulation of air between the shields 40 and 45 may be created by a fan 51 secured to the shaft 16 within the enclosed space. A set screw 52 may be employed for securing the fan to the shaft. The fan blades may be flat or curved and aligned with the shaft axis or inclined to the axis to draw air back forcibly against the shield 40, as shown.

By the provision of a removable cover plate 54 of sufficient size on the manifold 18, the entire motor and spinner cup assembly may be readily removed from the door assembly carried on the plate 38. Bolts 55 provide a convenient means of connecting the parts.

The double spaced shields and forced air circulation therebetween provide adequate protection for the motor and bearings even when placed very close to the hot air manifolds. The air circulates in an effective manner, the cool air being drawn in over that part of the motor nearest the shields and passing out in a wall or sheet between the shields. It is found that this apparatus is very effective, keeping the motor and bearing temperatures down to about 100° F. above prevailing room temperatures. Thus, if room temperature is 70° F., the motor temperature can be kept as low as 170° F., which is well within the limit of 300° F. which must be maintained to preserve the motor and bearings. The apparatus provided is simple and effective and may be readily installed on existing equipment where it is desired to raise the temperature of the combustion air supply for greater efficiency.

While one embodiment of the invention has been specifically described to illustrate the principles of the invention, it is to be understood that the invention may have various embodiments within the scope of the following claims.

I claim:

1. In an oil burner installation in which the air for combustion is highly preheated before introduction into the combustion chamber, and in which the driving motor and all of the bearings for the burner rotating shaft are located outside the combustion chamber and outside, but closely adjacent, the preheating manifold, means for cooling said bearings to a relatively low temperature, comprising, a shield between said manifold and said motor and bearings, and suction means mounted between said shield and said motor and partially enclosed in a chamber of which said shield forms one wall, for drawing cool air past the adjacent end of the motor and the adjacent set of bearings into said partially enclosed chamber to impinge against said shield, and thence to escape from said chamber.

2. In an oil burner installation in which the air for combustion is highly preheated before introduction into the combustion chamber, and in which the driving motor and all of the bearings for the burner rotating shaft are located outside the combustion chamber and outside, but

closely adjacent, the preheating manifold, means for cooling said bearings to a relatively low temperature, comprising, a conical, outwardly flared shield between said manifold and said motor and bearings, and suction means mounted between said shield and said motor and partially enclosed in a chamber of which said shield forms one wall, for drawing cool air past the adjacent end of the motor and the adjacent set of bearings into said partially enclosed chamber to impinge against said shield and thence to escape from said chamber.

3. In an oil burner installation in which the air for combustion is highly preheated before introduction into the combustion chamber, and in which the driving motor and all of the bearings for the burner rotating shaft are located outside the combustion chamber and outside, but closely adjacent, the preheating manifold, means for cooling said bearings to a relatively low temperature, comprising, a conical, outwardly flared, radially vaned shield between said manifold and said motor and bearings, and suction means mounted between said shield and said motor and partially enclosed in a chamber of which said shield forms one wall, for drawing cool air past the adjacent end of the motor and the adjacent set of bearings into said partially enclosed space to impinge against said shield and thence to escape from said chamber.

4. In an oil burner installation in which the air for combustion is highly preheated before introduction into the combustion chamber, and in which the driving motor and all of the bearings for the burner rotating shaft are located outside the combustion chamber and outside, but closely adjacent, the preheating manifold, means for cooling said bearings to a relatively low temperature, comprising, a conical, outwardly flared shield and a base plate shield clamped thereto at points but spaced therefrom except at said points, both shields being disposed between said manifold and said motor and bearings, said base plate shield being open at the center, and a fan on the shaft between said shields for drawing cool air past the adjacent end of the motor and the adjacent set of bearings through said central opening to impinge upon said outwardly flared shield and forcing it out between said shields.

5. In an oil burner installation in which the air for combustion is highly preheated before introduction into the combustion chamber, and in which the driving motor and all of the bearings for the burner rotating shaft are located outside the combustion chamber and outside, but closely adjacent, the preheating manifold, means for cooling said bearings to a relatively low temperature, comprising, a conical, outwardly flared shield and a base plate shield clamped thereto at points but spaced therefrom except at such points, both shields being disposed between said manifold and said motor and bearings, said base plate shield being open at the center, and a fan on the shaft between said shields for drawing cool air past the adjacent end of the motor and the adjacent set of bearings through said central opening to impinge upon said outwardly flared shield and forcing it out between said shields, said conical shield being provided with interior radial vanes.

6. In an oil burner installation in which the air for combustion is highly preheated before introduction into the combustion chamber, and in which the driving motor and all of the bearings for the burner rotating shaft are located

outside the combustion chamber and outside, but closely adjacent, the preheating manifold, means for cooling said bearings to a relatively low temperature, comprising, an outwardly flared shield and a substantially flat base plate shield spaced therefrom but removably secured thereto, both shields being mounted axially on a common shaft and between said manifold and said motor and bearings, the shield disposed on the motor side

being open adjacent the shaft, and a fan mounted on said shaft between the shields and adjacent the opening for drawing cool air in between the shields past the adjacent portion of the motor and the adjacent bearings to cool the same, said air thereafter flowing out at the periphery of said base plate shield.

FLOYD W. BENTLEY.
